UNITED STATES PATENT OFFICE.

RICHARD H. THOMAS, OF CHICAGO, ILLINOIS.

AUTOMATIC-CONTROL HEATING PLANT.

Application filed March 9, 1925. Serial No. 14,083.

To all whom it may concern:

Be it known that I, RICHARD H. THOMAS, a citizen of the United States, and a resident of the city of Chicago and State of Illinois, have invented certain new and useful Improvements in an Automatic-Control Heating Plant; and I do hereby declare that the following is a full, clear, and exact description of the same, reference being had to the accompanying drawings and to the numerals of reference marked thereon, which form a part of this specification.

This invention relates to a condensing and vacuum producing apparatus to be incorporated in steam heating systems to maintain the steam pressure in the radiators below atmospheric pressure to assure more rapid steam circulation.

It is an object of this invention to simultaneously remove the water of condensation and any air that may have leaked into the heating system and to periodically return the water to the boiler at a higher pressure than exists in the boiler, so that the possibility of back flow from the boiler into the device of this invention will be eliminated. At the same time the entrained air is intended to be separated from the water and discharged to the atmosphere.

It is another object of this invention to provide an intermittently operated device wherein an increase in the level of the water in the tank closes an air relief valve and builds up the required pressure in the tank to open a discharge valve leading to the boiler.

It is a further object of this invention to provide a quick-closing air valve which will be accelerated in action by the energy and impact of the air discharging through said valve.

It is also an object of this invention to provide an easily removed sediment trap and screen on the vacuum line from the radiators whereby scale and the like will be separated from the water of condensation.

Other and further important objects of this invention will be apparent from the disclosures in the specification and accompanying drawings.

This invention (in a preferred form) is illustrated in the drawings and hereinafter more fully described.

On the drawings:

Figure 1 is a side elevation of a device embodying features of this invention.

Fig. 2 is an end view thereof.

Fig. 3 is an enlarged partly sectional view corresponding to Fig. 1.

Fig. 4 is a section on the line 4—4 of Fig. 3.

Fig. 5 is a reduced section of the tank details not sectionalized in Fig. 3.

Fig. 6 is an end view of the removable screen.

Fig. 7 is an enlarged section of the air valve.

As shown on the drawings:

A return pipe from a system of steam radiators is indicated by the numeral 10 which leads into a sediment trap 11 formed in one end of a rectangular vacuum tank 12, which is mounted on a sub-base 13, and which serves in turn to support a cylindrical pressure tank 14. The sediment trap 11 is provided with a hand hole cover 15 and a blow off valve 16, the hand hole being provided for access to a cup-shaped removable screen 17 extending through the partition 18 into the vacuum tank 12. A pipe 19 leads from the vacuum tank to the suction chamber 20 of an injector or parallel injectors 21, which discharge into the pressure tank below the normal water level therein. A check valve 22 is provided in the pipe 19 to prevent backflow.

A motor driven centrifugal pump 23 draws water from the pressure tank through the connection 24 and normally discharges through a connection 25 and manifold 26 leading to the pressure nozzle 27 of the injector 21 back into the pressure tank through the suction nozzle 28. A branch pipe 29 on the discharge side of the centrifugal pump has a diaphragm type regulating valve 30 therein which is controlled by the pressure within the tank 14 communicated through a pipe 31, an increase in pressure up to a predetermined point serving to open the valve 30 against spring pressure which normally holds the valve closed at pressures below the desired point.

The pressure tank is provided with an air relief valve operated by a float 32. The air valve comprises a cylindrical body 33 seating in a suitable aperture in the tank and having a depending yoke 34 to serve as a valve stem guide. A tubular valve seat 35 is adjustably mounted in the top of the body 33 and can be screwed in and out thereof to vary the closing point of the valve relative to the water level within the

tank. The valve itself comprises a disc 36 preferably of rubber or the like, adapted to contact the end of the seat 35 and therefore of greater diameter than the clear diameter of the valve outlet, and a backing piece 36 secured on a valve stem 37 between nuts 38 to allow further adjustment of the closing position of the valve. The lower end of the valve stem 37 terminates in a yoke having 10 an oblong slot 38 through which a pin 39 on the float lever engages. The purpose of the oblong slot is to provide a take-up or lost motion between the float and valve. As the float rises, it lifts the valve with the 15 pin engaging at the top of the slot. As the valve approaches its seat the rush of air past the valve, because of its increased diameter and the restricted passage about the periphery of the valve disc, causes the valve to 20 close suddenly in advance of the float movement. Conversely, the valve is held closed by the pressure within the tank until the water level has fallen sufficiently to bring the pin 39 to the bottom of the slot 38, thus 25 causing the discharge of considerable fluid at each cycle of operation and eliminating hunting troubles due to rapid fluctuation of the valve with slight changes of water level.

A control box is illustrated at 40 together 30 with a vacuum gauge 41. This box contains a vacuum motor control switch of well known form which serves to maintain the vacuum within the tank 12 between predetermined limits by shutting off the motor 35 and pump when the degree of vacuum reaches a desired figure and starting the motor again when the degree of vacuum falls below a limiting figure.

The operation is as follows:

40 Assuming that the apparatus is connected into the heating system as hereinbefore described, the pressure tank is first filled with water, through the air valve, to a point several inches above the level of the injectors, 45 in fact, the tank may be filled to the point where the air valve is automatically closed by the float. On starting up the motor and pump, the latter, which has been primed by filling the tank, draws water from the pressure 50 tank through the connection (24) and delivers it to the pressure nozzle 27 of the injector which creates a suction on the line 19 leading to the vacuum tank and draws a mixture of condensed water, steam, and 55 air therethrough from the radiator return pipe, discharging into the pressure tank where the steam is condensed and the air separated from the water, the air discharging 60 to the atmosphere until the water level rises to a point where the air valve is closed, thereafter a pressure is built up in the tank until the diaphragm valve is opened thereby, when the pump discharges to the boiler until such time as the air valve opens 65 again and releases the pressure in the tank

as previously described. Because of the check valve in the line between the vacuum and pressure tanks, the vacuum is not affected by the partial cessation of the working of the injectors during the time the 70 pump is discharging to the boiler, so that a continuous vacuum is maintained on the return pipe from the radiators.

I am aware that numerous details of construction may be varied through a wide 75 range without departing from the principles of this invention, and I therefore do not purpose limiting the patent granted otherwise than necessitated by the prior art.

I claim as my invention:

1. In a device of the class described a piping system, a tank, a return from said piping system to said tank, a second tank, a power driven pump, a jet pump, connections whereby said power pump receives 85 water from said second tank and delivers it to either the jet pump or the piping system, a connection between said first tank and the jet pump, a float controlled air relief in said second tank and an automatic pressure valve 90 in the connection from the power driven pump to the piping system adapted to open in response to the pressure created in the second tank when the air relief valve is closed. 95

2. In a device of the class described, a piping system, a tank, a return from said piping system to said tank, a second tank, a power driven pump, a jet pump, connections whereby said power pump receives 100 water from said second tank and delivers it to either the jet pump or the piping system, a connection between said first tank and the jet pump, a float controlled air relief in said second tank, an automatic pressure valve in 105 the connection from the power driven pump to the piping system adapted to open in response to the pressure created in the second tank when the air relief valve is closed, a motor connected to said power driven pump, 110 and an automatic control therefor responsive to the degree of vacuum created in said first tank by said jet pump.

3. In a device of the class described, two tanks, a pump receiving water from one of said tanks and normally delivering it to the same, means controlled by the pressure in said last mentioned tank for diverting a portion of the delivery of said pump from said tank, and means operated by the stream 115 created by said pump for moving the contents of the first tank into the second tank. 120

4. In a device of the class described, a tank, a jet pump in said tank below the usual level of water therein, a power pump and connections whereby the water in said tank is circulated through said jet pump, and an air relief valve in the upper side of said tank comprising a valve mechanism, a float valve, and a lost motion connection 125 130

therebetween, whereby the rush of air past said valve will accelerate the final stage of the closure of said valve.

5. A water tank, a jet pump therein, a power driven pump for circulating the water in said tank through said jet pump, a float controlled air valve closed by a high water level in said tank, a branch connection from said power driven pump to an outside receiver, a pressure controlled valve in said last mentioned connection, and a connection from said tank to said last mentioned valve whereby said valve is opened when the pressure in said tank reaches a desired figure.

15. 6. In a device of the class described, a closed tank, a power pump, a connection from the delivery side of said pump to said tank, a second connection from the delivery side of said pump to a point outside the tank, a valve in said second connection, means controlled by the pressure within said tank for opening said valve, an air relief valve for said tank and means whereby said relief valve will be intermittently closed to build up a pressure within the tank sufficient to open said first mentioned valve.

7. In a device of the class described, a system of piping, a motor, a pump driven thereby, connections whereby the pump intermittently delivers water to the system of piping and withdraws water and air therefrom, means governed by the degree of vacuum in the system for controlling the motor, and means governed jointly by the water level and pressure for controlling the delivery of water from the pump to the system of piping.

40. 8. In a device of the class described, a pressure tank, a vacuum tank, a supply pipe from said pressure tank to a heating system, a return pipe from said heating system to the vacuum tank, pumps in series adapted to generate pressure in one tank and create vacuum in the other tank, means for trans-

ferring a portion of the contents of the pressure tank to the heating system upon the pressure therein reaching a predetermined value.

9. In a device of the class described, a pressure tank, a vacuum tank, a supply pipe from said pressure tank to a heating system, a return pipe from said heating system to the vacuum tank, pumps in series adapted to generate pressure in one tank and create vacuum in the other tank, means for transferring a portion of the contents of the pressure tank to the heating system upon the pressure therein reaching a predetermined value, and means for relieving the pressure in said second tank after the delivery of a portion of the contents thereof.

10. In a device of the class described, a pressure tank, a vacuum tank, a sediment chamber adapted to receive the condensate from a heating system, and a removable screen between the sediment chamber and the vacuum tank.

11. In a device of the class described, a pressure tank, a float therein, an air relief valve stem having a lost motion connection to the float, a valve disc adjustably mounted on said stem, and a valve cage and a valve seat adjustably mounted therein of smaller diameter than said disc whereby the rush of air past said disc as it approaches its seat will suddenly complete the closure of said valve.

12. In a device of the class described, a power driven pump, a jet pump operated thereby, a tank in which said jet pump is situated, and means controlled by the pressure within said tank to intermittently divert a portion of the delivery of said power driven pump from said tank to an external point.

In testimony whereof I have hereunto subscribed my name.

RICHARD H. THOMAS.
